UNITED STATES PATENT OFFICE.

CALVIN W. PARSONS, OF SCRANTON, PENNSYLVANIA, ASSIGNOR OF ONE-HALF TO THOMAS J. FOSTER, OF SAME PLACE.

SCREEN AND SEPARATOR FOR COAL, &c.

SPECIFICATION forming part of Letters Patent No. 566,793, dated September 1, 1896.

Application filed July 9, 1894. Serial No. 516,947. (No model.)

To all whom it may concern:

Be it known that I, CALVIN W. PARSONS, a citizen of the United States, residing at Scranton, in the county of Lackawanna and State 5 of Pennsylvania, have invented certain new and useful Improvements in Screens and Separators for Coal and other Materials; and I do declare the following to be a full, clear, and exact description of the invention, such as will 10 enable others skilled in the art to which it appertains to make and use the same, reference being had to the accompanying drawings, and to the letters and figures of reference marked thereon, which form a part of this specification. 15

The object of my invention is to afford a more convenient, economical, and effective screen and separator for separating or grading coals and other materials than those 20 heretofore in use.

My invention consists in the construction, combination, and arrangement of parts, as hereinafter fully set forth and claimed.

In the accompanying drawings, forming a 25 part of this specification, Figure 1 is a side view or elevation of one of my separators, partly in section. Fig. 2 is a top view of the same. Fig. 3 is a vertical cross-section of the upper part of Fig. 1 on the line *x y*. Fig. 4 is 30 a view in isometric perspective of the upper table of one of my machines, showing the arrangement of the bars and their connection to the chain. Fig. 5 is a diagram showing the stationary bars of my screen in diverging positions. Fig. 6 is a diagram showing the stationary bars of my screen made in zigzag form.

Similar letters and figures of reference indicate similar parts throughout the several views.

Referring to the drawings, A represents 40 longitudinal stationary iron bars made of tapering iron with the thinner edges downward. These bars may have their upper edges plain, as shown in Fig. 4, or they may be made with offsets, as at 2 2, Fig. 7, designed to give greater agitation to the cross-bars which are to be propelled over them. The bars A are placed at a distance apart corresponding to the size of the coal, &c., to 45 be separated and their upper edges are in the same plane, so as to form a platform or

table over which the cross-bars B may be propelled in the direction indicated by the arrow. The cross-bars B, which may be round, square, or any desired shape, may be 55 attached to the links of the chain C, so that their ends become the pins or rivets of the links of their propelling-chain C, but any method of attachment will suffice, the principal requirements being that they be securely 60 attached, and that they be parallel at right angles to the table and at equal distances from one another. The longitudinal bars A may also be secured and supported in any desired manner, but must be well secured and equally distanced from one another. One of the principal features of my machine is in the arrangement of these sets of bars A and B. The arrangement is clearly shown in Fig. 4, where the near propelling-chain is 70 removed. It will be observed that the widths of the holes through which material may pass are determined by the distance between the longitudinal bars, and that the lengths of the said holes are determined by the distance between the cross-bars B. 75

The chains C pass over sprockets D and D', supported, respectively, by the bearings J and J', attached to the beam or sill K of the framework or base of the machine. A second series of longitudinal bars A' are arranged underneath, as indicated by the dotted lines in Fig. 2. These are placed closer together than the upper set, and thus are used to separate a size smaller than that separated by the upper set. The cross-bars are propelled over the lower set on their return run, as shown in Fig. 1. 85

5 and 6 in Fig. 1 are chutes for the purpose of conducting that which falls through 90 the upper bars to the head of the run on the lower bars.

E and E' are guard-strips to keep the material from falling off at the sides of the machine. 95

F is a tail-chute for conducting away the larger sizes separated by the upper run or table.

The hopper of the machine is represented at g, and it is fitted with a gate G, by which 100 the feed of the machine may be regulated.

If the arrangement of longitudinal bars,

as shown by the diagram in Fig. 5, is substituted for the arrangement shown in the first four figures, several grades or sizes may be separated in one run of the cross-bars. Thus 5 it will be seen that the mesh formed at 3 would separate a smaller size than the mesh at 4, and there would be intermediate sizes separated on the sections of the run between the lines N and O and the lines M and N. Partitions 10 may be located at these lines, and it is evident that the sizes of material which will fall into each bin thus divided off can be adjusted by moving the said partitions lengthwise of the machine. The bars A may be zigzagged concurrently in a horizontal plane, as shown in Fig. 6, which arrangement effectually precludes pieces from being carried along, partially supported by a cross-bar and partially by sliding contact with a longitudinal bar. This arrangement is found useful for grading wet coal.

The operation of my machine will now be readily understood. It will be assumed that coal is the material to be screened or separated.

The broken coal is fed into the hopper g and the gate G raised sufficiently to let the coal escape as fast as is desired on to the screening-table, composed of the bars A and the cross-bars B. Power is applied to the shaft d, Fig. 2, and the sprocket revolved so as to move the cross-bars in the direction indicated. The coal which is too large to pass through the upper screen is carried off the end of the machine and conducted away by the chute F. The smaller coal falls through and is caught by the chutes 5 and 6 and carried to the head of the bars A'. The sizes which are too large to pass between these bars, which are closer than the bars A, are carried beyond the end of the longitudinal bars A' and drop through between the cross-bars B, and are conducted away by the chute I. The smaller lumps, which pass through the lower bars A', may be further screened by means of other sets of bars, duplicates of the machine just described, except that the bars are closer than the foregoing, thus making a screen of finer mesh, and this process is followed out until the finest or smallest sizes desired are separated.

It will be obvious that by my invention I provide a screen comprising longitudinal bars which in one form may be arranged in an upper and a lower series and in another form be arranged in the same plane, in each

of which forms the longitudinal bars at one portion of their operative surface are arranged in closer relation to each other than at another portion of their said operative surface, whereby the coal in passing through said bars is graded.

Having thus described my invention, what I claim as new, and desire to secure by Letters Patent, is—

1. In an organized screening and grading machine of the kind described, the combination of a series of upper, and a series of lower longitudinal grading-bars, the distance between the bars of the one series being greater than the distance between the bars of the other series; an apron provided with transverse bars traveling over the said series of longitudinal bars in opposite directions, and means for moving said apron.

2. In a screening or grading machine of the kind described an upper table composed of equidistant fixed longitudinal bars, a lower table composed of a different series of equidistant fixed longitudinal bars, in combination with a continuous apron composed of the chains C, C, and the equidistant cross-bars B, B, and said apron being adapted to be drawn over the said upper and lower tables in opposite directions by means of the driving-wheels D, D'; and the cross-bars of the said apron adapted to coöperate with the fixed longitudinal bars of each series so as to form the transverse components of the meshes of the screens substantially as shown.

3. In a screening or grading machine of the kind described, the combination of an upper table composed of a series of fixed longitudinal bars, a lower table composed of a series of fixed longitudinal bars in closer relation than those of the upper table; and the apron composed of the chains C, C and cross-bars B, B adapted to be drawn over said upper and lower tables in opposite directions by means of the driving-wheels D, D'; and the cross-bars B of said apron adapted to coöperate with each series of longitudinal fixed bars so as to form the transverse components of the meshes of the screens, substantially as shown.

In testimony whereof I affix my signature in presence of two witnesses.

CALVIN W. PARSONS.
